CHARLES F. LINDEBURG, OF NEWARK, NEW JERSEY.

GLASS-CUTTING MACHINE.

1,204,039.

Specification of Letters Patent. Patented Nov. 7, 1916.

Application filed November 10, 1915. Serial No. 60,637.

To all whom it may concern:

Be it known that I, CHARLES F. LINDEBURG, a citizen of the United States, and a resident of Newark, in the county of Essex and State of New Jersey, have invented certain new and useful Improvements in Glass-Cutting Machines, of which the following is a specification.

This invention relates to that class of glass cutting machines for cutting disks of glass, and the objects of the invention are to provide a machine in which an even pressure may be applied in scoring the glass; to thus obtain a clean and accurate cut; to provide a construction in which the tool is rotated by power; to rotate the tool only while it is lowered toward the glass; to permit the cutter to be readily removed and replaced; to cause the cutter to remain tangent to the scored circle at whatever point it rests; to secure simplicity of construction and operation, and to obtain other advantages and results as may be brought out in the following description.

Referring to the accompanying drawings, in which like numerals of reference indicate the same parts throughout the several views, Figure 1 is a side elevation of a glass cutting machine embodying my invention; Fig. 2 is an end view of the same looking at the right hand end of Fig. 1; Fig. 3 is a longitudinal vertical section on line A—A Fig. 2, and Fig. 4 is a perspective view of the tool, partially broken away to disclose the mounting of the cutter.

In the specific embodiment of the invention illustrated in said drawings, the reference numeral 1 indicates a supporting frame providing a foot 2 by which the frame may be secured to a suitable bench and formed integrally therewith is an upright 3 with which is integrally formed a pair of lateral arms 4, 5 extending preferably in the opposite direction from the foot and adapted, when the foot is held fast, to extend substantially parallel above the bench. These arms are spaced apart and substantially parallel to each other, one, as 4, being at the upper end of the upright 3 and the other part way down the upright. At their ends away from the upright, the arms are connected by a brace 6 preferably parallel to the upright.

Alined bearings 7, 8 are provided in the arms 4, 5 adjacent the ends thereof toward the brace 6, and in the same is mounted ro-

tatably and slidably a spindle 9 which is held thereby substantially parallel to the upright 3 and perpendicular to the supporting surface or bench. The upper end 60 of this spindle is preferably semi-spherical and seated upon the same is a knob or handle 10 prevented from displacement by any suitable means, such as by providing a slot 11 circumferentially of the spindle and passing a pin 12 through the knob to engage within said slot. By this means, the knob is longitudinally stationary upon the spindle but may be freely rotated thereon. Between the knob 10 and the bearing 7 is a spiral 70 spring 13 under compression so as to normally force the knob and spindle upward.

Rotatably carried upon the spindle between the arms 4, 5 is a loose pulley 14, preferably held normally upward upon the 75 spindle by a spring 15 between itself and the lower arm 5. A stop 16 integral with the brace 6 and projecting inwardly over the pulley 14 limits upward movement of the pulley. Clutch means are provided for 80 driving the spindle 9 from the pulley 14 adapted to automatically engage as the spindle is lowered, and such means I have shown as providing a clutch member 17 integral with respect to the pulley 14 and having upwardly extending ears 18. Above the pulley and secured upon the spindle as by a transverse pin 19 is a co-acting clutch member 20 having shoulders 21 adapted to engage the ears 18. This co-acting clutch 85 member is positioned upon the spindle so as to be released from the other member 17 when the spindle is drawn upward to its normal position, and preferably the member 20 forms a stop adapted to engage the under side of the upper arm for limiting the upward movement of the spindle. When the upper clutch member 20 is raised and in engagement with the upper arm 4 the spring 15 raises the pulley 14 into engagement with the stop 16, and the stop 16 is so placed that the clutch members are at such time held out of engagement with each other. Accordingly the pulley may be rotated freely and will not rotate the spindle. However, as the operator presses downward on the knob 10 the clutch member 20 will come into engagement with the clutch member 18 on the pulley and start rotation of the spindle, after which further depression of the knob 10 will lower the pulley away from the stop 16 but will still retain the clutch members in

operative engagement so that the spindle rotates. On the upright 3 and transverse thereto adjacent its upper end is a bearing 22 in which is mounted an axle 23 projecting at the opposite sides of the frame and having idler pulley wheels 24, 24 mounted upon said projecting ends. A belt 25 passes under one of these pulleys 24, then to the pulley 14 around the same, and back to the other pulley 24 passing under the same and from thence to any suitable power (not shown).

The lower end of the spindle 9 below the lower arm 5 of the frame is preferably squared as at 26 and is transversely apertured as at 27 to receive a tool 28. This tool comprises a squared shank portion 29 adapted to be inserted in the aperture 27, and one end of the shank as 30 is bent at 20 substantially right angles so as to depend from the horizontal portion of the shank. This depending portion 30 is provided with a long socket 31 opening downward and adapted to rotatably receive the upper end 25 of a cutter 32. It will be understood that the socket 31 and the end of the cutter inserted therein are both cylindrical, conical at their upper ends and of substantially the same diameter so that the cutter will turn 30 freely therein. A downwardly facing shoulder 33 is provided circumferentially of the cutter at a distance from its upper end substantially equal to the depth of the hole, so that the shoulder is at the lower end of the depending portion 30 when the cutter is inserted in position therein. A suitable latch is adapted to engage under the shoulder for holding the cutter in place and for illustrative purposes this latch is shown as a leaf spring 34 extending longitudinally of the depending portion 30 of the tool and tending to normally lie flatwise thereagainst. Said leaf spring is secured at its upper end to the depending portion of the tool as by 40 a screw 35 and at its lower end is provided with a transverse portion 36 adapted to extend under the lower end of the depending portion of the tool and notched as at 37 inwardly from its free end to take around 45 the cutter below the shoulder 33. It will be understood that the notch is small enough so that the upper end of the cutter cannot pass through the same and thus when the leaf spring is lying flatwise against the depending portion of the tool the cutter will 50 be rotatably held in position, but to remove the same it is only necessary to draw the leaf spring outward to disengage the shoulder at which time the cutter may be slipped 55 out. At the lower end of the cutter is provided a scoring wheel 38 which will engage and score the glass as the spindle is lowered and rotated. In order that the scoring wheel 60 may stand in tangential relation to the scored circle at whatever point it rests the 65

lower end of the cutter is curved in a plane transverse to the pivoting of the scoring wheel, so that the lowest point of the scoring wheel resting upon the glass will not be on the center line of the straight portion of 70 the cutter. Consequently, as the tool is swung around, the scoring wheel will lag and thus hold its proper relation to the circle being scored. For varying the diameter of the circle thus scored, the horizontal shank portion of the tool may be adjusted 75 within the aperture 27, and a screw 39 is arranged in the spindle to clamp the tool at such adjusted position, the present disclosure showing the screw inserted transversely 80 of the spindle. The lower end of the spindle below the tool is split in the plane of the tool and spindle and the ends thus obtained may be drawn together by the screw 39 to clamp the tool.

To rotate the tool in operation of the machine the operator presses down upon the knob 10, overcoming first the pressure of the spring 13 and then the pressure of both that spring and the spring 15 as the clutch members are engaged and the pulley wheel is lowered away from its stop 16, until the scoring wheel thus caused to revolve engages the work and cuts the same. Obviously no attention has to be paid to rotating the tool, as that occurs automatically, and the operator may retain an even pressure upon the knob so as to obtain an even scoring and consequently a clean cut. When the operator releases the knob 10 the spring 13 raises the spindle until the clutch member 20 engages the upper arm 4 of the frame and the spring 15 raises the pulley 14 until it engages the stop 16, and the spindle and tool remain at rest until lowered onto another piece of glass.

Obviously detail modification and changes may be made in the manufacture of my improved glass cutting machine without departing from the spirit and scope of the invention, and I do not wish to be understood as restricting myself except as required by the following claims when construed in the light of the prior art.

Having thus described the invention, what I claim is:

1. In a device of the character described, the combination with a frame, of a spindle rotatably and slidably mounted in said frame, a cutting tool in said spindle, clutch members one fast on the spindle and the other loose, means for driving said loose clutch member, and means normally holding the spindle slid away from the work and the clutch thrown out, said parts being arranged and adapted so that pressure upon the spindle to engage the tool with the work throws in the clutch before said tool engages the work and holds it in engagement until the tool is withdrawn from the work.

2. In a device of the character described, the combination with a frame, of a spindle rotatably and slidably mounted in said frame, a tool in said spindle, a clutch member rotatably mounted upon the spindle, means for rotating said clutch member, and a co-acting clutch member fast upon the spindle and adapted to engage or be released from the first-mentioned clutch member as the spindle is slid in one direction or the other.

3. In a device of the character described, the combination with a frame, of a spindle rotatably and slidably mounted in said frame, a tool in said spindle, a clutch member rotatably mounted upon the spindle, means for rotating said clutch member, a co-acting clutch member fast upon the spindle and adapted to engage or be released from the first-mentioned clutch member as the spindle is slid in one direction or the other, and means for retaining the clutch members separated when the spindle is slid in one direction.

4. In a device of the character described, the combination with a frame, of a spindle rotatably and slidably mounted in said frame, a tool in said spindle, a clutch member rotatably mounted upon the spindle, means for rotating said clutch member, a co-acting clutch member fast upon the spindle and adapted to engage or be released from the first-mentioned clutch member as the spindle is slid in one direction or the other, and means for sliding said spindle in the direction for normally releasing the clutch members.

5. In a device of the character described, the combination with a frame, of a spindle rotatably and slidably mounted in said frame, a tool in said spindle, a clutch member rotatably mounted upon the spindle, means for rotating said clutch member, a co-acting clutch member fast upon the spindle and adapted to engage or be released from the first-mentioned clutch member as the spindle is slid in one direction or the other, means for sliding said spindle in the direction for normally releasing the clutch members, and means for separating the clutch members as the spindle is slid by said sliding means.

6. In a device of the character described, the combination with a frame, of a spindle rotatably and slidably mounted in said frame, a tool in said spindle, a loose pulley rotatably mounted on said spindle and providing a clutch member, a co-acting clutch member fast upon the spindle and adapted to engage or be released from the clutch member on the pulley as the spindle is slid in one direction or the other, a spring for sliding the spindle in a direction to disengage the clutch members, a spring for sliding the pulley wheel in the same direc-

tion, and a stop for limiting the movement of the pulley wheel whereby the spindle may be slid farther than the pulley to disengage the clutch members.

7. In a device of the character described, the combination with a frame, of a spindle rotatably and slidably mounted in said frame, a cutting tool in said spindle, clutch members one fast on the spindle and the other loose, means for driving said loose clutch member, means normally holding the spindle and loose clutch member slid away from the work, and a stop for limiting such sliding of the loose clutch member so that the fast clutch member will be carried out of engagement with it.

8. In a device of the character described, the combination with a frame providing a pair of parallel horizontal arms spaced apart and providing vertically alined bearings, of a spindle rotatably and slidably mounted in said bearings, a tool in said spindle, a pulley wheel rotatably mounted on the spindle between the arms of the frame and providing a clutch member at its top, a co-acting clutch member fast upon the spindle between the pulley wheel and the upper arm of the frame, a spring for holding the pulley wheel normally upward upon the spindle, a stop for limiting upward movement of said pulley wheel, and means for sliding the spindle upward to disengage the clutch members.

9. In a device of the character described, the combination with a frame providing a pair of parallel horizontal arms spaced apart and providing vertically alined bearings, of a spindle rotatably and slidably mounted in said bearings, a tool in said spindle, a pulley wheel rotatably mounted on the spindle between the arms of the frame and providing a clutch member at its top, a co-acting clutch member fast upon the spindle between the pulley wheel and the upper arm of the frame, a spring for holding said pulley wheel normally upward upon the spindle, a stop for limiting upward movement of said pulley wheel, means for sliding the spindle upward to disengage the clutch members, said co-acting clutch member adapted to engage the upper arm of the frame and limit upward movement of the spindle.

10. In a device of the character described, the combination with a frame and a spindle rotatably and slidably mounted in said frame, of a tool having a shank portion adjustably mounted transversely of said spindle at its lower end and having a depending portion, a cutter mounted in said depending portion having its lower end curved out of alinement with the upper end and having a scoring wheel rotatably mounted in the same plane in which the cutter is curved.

11. In a device of the character de-

- scribed, the combination with a frame and a spindle rotatably and slidably mounted in said frame, of a tool having a shank portion adjustably mounted transversely of said spindle at its lower end and having a depending portion, a cutter mounted in said depending portion having its lower end curved out of alinement with the upper end and having a scoring wheel rotatably mounted in the same plane in which the cutter is curved, and means releasably securing the cutter in position.
12. In a device of the character described, the combination with a frame and a spindle rotatably and slidably mounted in said frame, of a tool having a shank por-

tion adjustably mounted transversely of said spindle at its lower end and having a depending portion, a cutter mounted in said depending portion having its lower end curved out of alinement with the upper end and having a scoring wheel rotatably mounted in the same plane in which the cutter is curved, a leaf spring at the side of said depending portion of the shank of the tool having a transverse portion adapted to extend under the lower end of said depending portion, said cutter having a downwardly facing shoulder under which the transverse portion of the leaf spring is adapted to engage for retaining the cutter in position.

CHARLES F. LINDEBURG.
